UNITED STATES PATENT OFFICE.

FRANK C. ALTMANN, OF NEW HAVEN, CONNECTICUT, ASSIGNOR TO THE ENGLISH & MERSICK CO., OF NEW HAVEN, CONNECTICUT, A CORPORATION.

LATCH.

1,074,340.

Specification of Letters Patent.

Patented Sept. 30, 1913.

Application filed May 26, 1913. Serial No. 769,886.

To all whom it may concern:

Be it known that I, FRANK C. ALTMANN, a citizen of the United States, residing at New Haven, in the county of New Haven and State of Connecticut, have invented a new and useful Improvement in Latches; and I do hereby declare the following, when taken in connection with the accompanying drawings and the characters of reference 10 marked thereon, to be a full, clear, and exact description of the same, and which said drawings constitute part of this application, and represent, in—

Figure 1 a face view of a latch constructed in accordance with my invention and shown as attached to a door. Fig. 2 a similar view indicating the arrangement of operating handle out of line with the latch. Fig. 3 an inner face view of the lever for 20 operating the latch. Fig. 4 an inside view of the latch shown with the bolt in its thrown position. Fig. 5 a similar view with the bolt retracted.

This invention relates to an improvement 25 in latches and particularly to latches for vehicle doors.

The object of this invention is to provide a latch the bolt of which may be easily moved and in which the operating handle 30 may be located at any convenient point; and the invention consists in the construction hereinafter described and particularly recited in the claim.

In carrying out my invention I employ a 35 latch case 2 carrying a horizontally movable latch bolt 3 the nose 4 of which projects beyond the face plate 5 in the usual manner. This latch bolt is normally thrown forward

by a spring 6 and is adapted to be retracted by a wedge 7 having a cam face 8 co-acting 40 directly with the tail of the bolt or with an antifriction roller 9 mounted thereon. This wedge is provided with an upwardly extending arm 10 which may be located between rollers 11 and 12, and is adapted to have a 45 chain or cord 13 attached to its upper end, this chain extending to an operating handle 14 mounted in any convenient point. This handle may be connected with a cam 15 which will move the chain and the chain 50 may extend directly from the cam downward to the wedge 7, or it may be passed over one or more pulleys or rollers 16 so that the operating handle may be located at any convenient point on the door. If desired, the bolt may also be provided with an upwardly extending bowed arm 17 to be 55 acted upon by a roll-back 18 having a hub 19 which may be turned by the usual knob spindle. 60

I claim:

A latch comprising a horizontally movable bolt, a vertically movable wedge co-acting with the bolt whereby the upward movement of the wedge will retract the bolt, 65 an operating handle, and a flexible connection between the operating handle and wedge.

In testimony whereof, I have signed this specification in the presence of two subscribing 70 witnesses.

FRANK C. ALTMANN.
